GEORGE LAMMADIN AND DAVID F. STONE, OF BRIDGEPORT, CONNECTICUT,
ASSIGNORS TO THE UNION METALLIC CARTRIDGE COMPANY, OF BRIDGE-
PORT, CONNECTICUT, A CORPORATION OF NEW YORK.

CARTRIDGE-SHELL.

SPECIFICATION forming part of Letters Patent No. 692,154, dated January 28, 1902.

Application filed July 31, 1901. Serial No. 70,370. (No model.)

To all whom it may concern:

Be it known that we, GEORGE LAMMADIN and DAVID F. STONE, citizens of the United States, residing at Bridgeport, county of Fairfield, State of Connecticut, have invented a new and useful Method of Fixing Priming in Cartridge-Shells, of which the following is a specification.

Our invention has for its object to provide means for fixing the priming in cartridge-shells, more especially rim-fire shells, using "nitrated" or "smokeless" powders, so called. It is of course well understood that in all rim-fire cartridge-shells the priming is placed around the inner edge of the base of the shell and is exploded by a blow upon the base of the shell at the rim or edge thereof. Under ordinary conditions the detonation of the priming is almost certain to take place upon the delivery on the rim of the shell of the blow of the firing-hammer. It is possible, however, owing to the elasticity of smokeless powder, to the fact that it may not be packed closely in the shell, and, furthermore, to the fact that there has heretofore been no means of retaining the priming securely in place to meet the blow of the firing-hammer, that an occasional shell in a large number will fail to explode under ordinary firing conditions, the priming yielding and being displaced inward slightly, but without being detonated. Our invention overcomes this objection, so that any one of a large number of rim-fire cartridge-shells loaded with smokeless powder will be perfectly certain to explode under ordinary firing conditions.

In order to accomplish the desired result, we fix the priming rigidly in place by means of a retaining-cement having the properties of being plastic while wet, of drying hard and firm, and of rapid deflagration when ignited. These results require a mixture containing both carbon and oxygen in large proportions.

We wish it distinctly understood that our

invention is not limited to any special compound or retaining-cement, as various compounds will produce the desired result. In practice we have experienced perfectly satisfactory results from the use of a cement consisting of approximately two parts chlorate of potash and one part of starch. The proportions of this compound may be varied to meet the requirements of use, and other organic compounds rich in carbon may be substituted for starch—for example, fine sawdust or dextrin. We recommend the use of starch, however, as when mixed with chlorate of potash in substantially the proportions stated and wet with water it makes an adhesive paste which dries hard and remains firm and deflagrates rapidly when ignited. Should sawdust be used instead of starch, the compound may be made more or less adhesive, as may be required by the use additionally of a small quantity of gum-tragacanth or gum-arabic. In lieu of chlorate of potash picrate of ammonia or picrate of potash may be used mixed with sawdust, or saltpeter may be mixed with gum-tragacanth or gum-arabic in the parts of two or three to one, or a slow nitro-glycerin compound may be used with the same general result—for example, a small percentage of nitro-glycerin mixed with infusorial earth or sawdust.

In the accompanying drawings, forming part of this specification, Figure 1 is an elevation of a loaded cartridge, the position of the priming-retaining cement being indicated by a dotted line; and Fig. 2 is a section of a cartridge-shell, showing a rim-fire priming retained in place by a cement.

10 denotes a cartridge-shell, 12 a rim-fire priming lying around the base of the shell on the inner side, and 13 a layer of highly-inflammable cement by which the priming is securely retained in place, so that it will not yield to the blow of a firing-hammer, but will be detonated or exploded thereby and will set fire to the cement, which is so highly

inflammable as to make its instantaneous combustion certain if the priming is detonated, and consequently the instantaneous firing of the powder charge.

- 5 In preparing the cartridge-shell for loading after the priming has been placed therein a layer of the inflammable cement is molded down firmly upon the priming and then dried, after which the operation of loading may be 10 proceeded with in the usual manner.

Having thus described our invention, we claim—

The combination with a cartridge-shell, of

a priming lying in the base thereof and a layer of plastic, hard-drying and highly-inflammable cement molded in the shell over the priming by which the priming is retained in place and deflagration thereof under firing conditions is rendered certain.

In testimony whereof we affix our signatures in presence of two witnesses.

GEORGE LAMMADIN.
DAVID F. STONE.
